UNITED STATES PATENT OFFICE.

LEO A. MULLEN, OF COLLINGDALE, PENNSYLVANIA, AND JOSEPH JACKEVICH, OF MERCHANTVILLE, NEW JERSEY.

DEVICE FOR IMPARTING UNIDIRECTIONAL MOVEMENT.

Application filed December 16, 1926. Serial No. 155,295.

Our invention relates to motion counters and more particularly to a device adapted to count the number of revolutions, reciprocations or oscillations of a given machine, and to close an electric circuit when a predetermined number of such movements have been made.

In order to simplify the disclosure of our invention, it will be illustrated and described as being applied to washing machines, such as are used in laundries, but it is to be understood that we do not wish to limit ourselves to this application as our invention may be readily applied to machines of various types.

The principal object of our invention is to provide a device that will count the number of movements, whether made in one or in opposite directions, and will indicate when a predetermined number of such movements have been made by either giving certain signals or by automatically stopping the machine.

Another object of our invention is to provide a device that may be readily applied to a wide range of machines without alterations to the device or to the machine and which is simple and inexpensive in construction.

These objects, and other advantageous ends which will be described hereinafter, we attain in the following manner, reference being had to the accompanying drawings in which:

Figure 1, is a front elevation of a preferred embodiment of our invention,

Figure 2, a central longitudinal sectional view of same, certain parts being shown in full,

Figure 3, a section on line 3—3 on Figure 2,

Figure 4, a section on line 4—4 on Figure 1,

Figure 5, a section on line 5—5 on Figure 1,

Figure 6, a diagram showing a certain application of our invention, drawn to a reduced scale.

Referring now more in detail to the drawing, the device as a whole is represented by the numeral 10; it has a casing 11 with ends 11^a and 11^b and a removable front plate 12 which is provided with a sight opening 13, preferably covered by a glass 14. A bracket 15, secured to the inner side of front plate 12, extends downwardly and has a scale 16

secured to its outer side so that the scale is 55 visible through sight opening 13.

A shaft 17, having coarse threads thereon, is journaled in the ends of casing 11 and held against longitudinal movement by a collar 18 and the squared end of the threaded portion abutting either side of a partition 19 disposed in one end of casing 11. A gauge 20 is threaded onto shaft 17 and is slidable upon a rod 21 extending through casing end 11^a and threaded into partition 19. A 65 pointer 22 is secured to gauge 20 and extends downwardly, forwardly and then upwardly into the space between scale 16 and glass 14. Shaft 17 is rotated by means of a knurled knob 17^a formed on its outer end and, as it 70 is held against longitudinal movement, rotation thereof will cause gauge 20 to move lengthwise on shaft 17 and thus bring pointer 22 over any desired graduation on scale 16. 75

Directly below shaft 17, a shaft 23 is rotatably mounted in the ends of casing 11 and extends through partition 19. It may be rotated by means of a knurled knob 24 and is held against longitudinal movement by 80 the hub of a ratchet wheel 25 fixed to the shaft between partition 19 and casing end 11^b. A rod 26 is mounted in casing end 11^a and in partition 19 immediately below shaft 23 and is adapted to hold an indicator 27, 85 which is threaded onto shaft 23 and slidably mounted on rod 26, against rotation. A pointer 28 is secured to indicator 27 and extends forwardly and then upwardly between scale 16 and glass 14 and has its forwardly 90 extended portion of such a length that it will pass pointer 22, as plainly shown in Figure 4.

A slide 29 is mounted on the inner side of casing end 11^b and is provided with a slot 95 30 through which the ends of shafts 17 and 23 extend; the length of slot 30 being slightly longer than the distance from the top of shaft 17 to the bottom of shaft 23 so that slide 29 may have a slight vertical movement on these shafts. An arm 31 extends from slide 29 and has a pawl 32 rockably mounted on its outer end and held in engagement with the teeth of ratchet wheel 25, by means of a spring 33 as plainly shown in 100 Figure 3. The lower end of slide 29 is provided with a foot 34 which extends through a suitable slot in casing end 11^b. 105

A slidable contact piece 35, having a vertical slot 36, is mounted on casing end 11^b by means of suitable shouldered screws 37 threaded into the end of the casing and engaging the sides of the slot. Contact piece 35 is provided at its lower end with a curved portion 38 which is connected to foot 34 by a coiled spring 39.

As slide 29 has an upward movement, due to the length of slot 30, of but little more than the distance between two teeth on the ratchet wheel 25, it is evident that by raising contact piece 35, spring 39 will move slide 29 upwardly and cause pawl 32 to rotate ratchet wheel 25 one notch. As it would be difficult to adjust the device to a machine so that the contacting part of the machine would move slide 29 the required distance to rotate ratchet wheel 25 one notch, slot 36 is made long enough to permit a range of adjustment of the contacting part of the machine. When contact piece 35 is moved upwardly, slide 29 is carried with it by spring 39 to the limit allowed by slot 30, after which contact piece 35 is allowed to continue upwardly by the resiliency of spring 39.

Gauge 20 is made of insulating material, such as bakelite, and has an electrical contact 40 secured to one lower corner and a spring contact 41 secured to its other lower corner and extending across the bottom of the gauge, so that its end is adjacent to but spaced from contact 40 with its central portion bowed downwardly, as shown in Figure 2. Indicator 27 is also of insulating material and has a rounded projection 42 formed on its upper side. Electric wires 43 connect contacts 40 and 41 with binding posts 44 and 45 mounted on the rear of casing 11.

Washing machines, such as are used in laundries, are usually designed to make a few revolutions in one direction and then a few in the opposite direction with the result that ordinary revolution counters would be of no practical use while, by employing our invention, it does not matter in which direction rotation takes place or whether the movement to be counted is reciprocating or oscillating.

Assuming that our invention has been applied to a battery of belt driven barrel washing machines, as shown in Figure 6, the device would be used in the following manner. Shaft 17 would be rotated to bring pointer 22 opposite the graduation on the scale representing the total number of revolutions required to perform the washing operation. Indicator 27 would be moved to the right until pointer 28 came opposite the zero mark on the scale. It is intended that a quick return shall be used on indicator 27 but, as there are several well-known methods of accomplishing this result, none have been illustrated or described. A wire 44^a would be

secured to binding post 44 and connected to a battery, indicated on the drawing by the character B, and a wire 45^a connected between binding post 45 and an annunciator, represented on the drawing by the character A. The battery and annunciator would be connected by means of a wire 46, as shown in Figure 6. Devices on additional machines would be connected similarly to the one described above, that is; wire 44^b would connect binding post 44 to the battery and wire 45^b would connect binding post 45 to its corresponding terminal on annunciator A, as shown diagrammatically in Figure 6.

Any number of washing machines can be equipped with our devices and the devices electrically connected to one or more annunciators. At the time of putting a new batch of clothes in each washer, the gauge on the device attached thereto would be set for the number of revolutions desired and the indicator set at zero, as above described. The machine is then set in motion by a button 47, attached to the end of the barrel of the washing machine, which comes in contact with curved portion 38 on contact piece 35 and raises same, thereby raising slide 29, actuating ratchet wheel 25 and moving indicator 27 along shaft 23 until pointer 28 overlaps pointer 22, at which time projection 42 will engage spring contact 41, force same against contact 40 and close the circuit. This will cause the bell on the annunciator to ring and the indicating hand on the annunciator to point to the number of the machine which has finished its operation.

As previously stated, washers of this type are designed to first rotate in one direction and then in the other but, by referring to Figure 5, it will be noted that the direction of rotation is immaterial as button 47 will raise contact piece 35 regardless of the direction from which it approaches, due to the shape and location of curved portion 38.

In case the machine, to which our device is attached, is driven by a motor, a solenoid operated switch may be connected into the signal circuit so that, when this circuit is closed as above described, the annunciator will show which machine has finished its operation and the switch will stop the motor. As the installation and operation of electromagnet switches are well-known, this feature will not be illustrated or described as it forms no part of this invention but merely forms another use to which our invention may be adapted.

It will be noted that the left hand end of shaft 23 is slightly smaller than the threaded portion, so that, in case indicator 27 runs past gauge 20 and the attendant fails to shut down the machine, the indicator cannot run against partition 19 and injure the device.

In order that shaft 23 may be turned in the direction opposite to that in which it is

rotated by ratchet wheel 25, we provide a plunger 48 which extends through front plate 12 and is adapted to engage the lower end of pawl 32 and hold same out of engagement with ratchet wheel 25. Plunger 48 is normally held out of contact with pawl 32 by means of a coil spring 49 disposed between a bracket 50 and a shoulder formed on the plunger.

10 While we have illustrated and described one embodiment of our invention, it will be readily understood that various modifications may be made without departing from the spirit thereof, and hence we do not wish 15 to limit ourselves to the construction set forth but consider that we are at liberty to make such changes and alterations as fairly come within the scope of the appended claims.

20 We claim:

1. A device for imparting unidirectional movement including a support having a slot, a shaft journaled in the support, a ratchet wheel fixed on the shaft, a slide on the support, a pawl hinged on the slide and engaging the ratchet wheel, a foot on the slide extending through the slot, a second slidable member mounted on the support and connected to the foot, and a contact member on 25 the slidable member adapted to be engaged and actuated by an external moving body.

30 2. A device for imparting unidirectional movement, including a support, a shaft journaled in the support, a ratchet wheel fixed on

the shaft, a slide on the support, a pawl hinged on the slide and engaging the ratchet wheel, a second slide on the support, a spring connecting the two slides, and a contact on the second slide adapted to be abutted by an external moving body.

35 3. A device for imparting unidirectional rotation to a shaft journaled in a support including a ratchet wheel fixed on the shaft, a slide on the support, stops on the support for limiting the movement of the slide, a 40 pawl hinged on the slide and engaging the ratchet wheel, a second slide on the support, a spring connecting the two slides, and a contact on the second slide adapted to be abutted by an external moving body.

4. A device for imparting unidirectional movement, including a support, a shaft journaled in the support; a ratchet wheel fixed upon the shaft; a slide on the support; stops upon the support; a pawl hinged on the slide 45 adapted to engage the ratchet wheel, the slide having a slot embracing the stops and adapted to limit the movement of the slide; a second slide, on the support; a spring connecting the two slides; a contact on the second slide, and a moving body mounted upon the support and adapted to engage the contact.

50 55 60 In testimony whereof we have signed our names to this specification.

LEO A. MULLEN.
JOSEPH JACKEVICH.
